UNITED STATES PATENT OFFICE.

SOLOMON KENDRICK, OF CHELSEA, MASSACHUSETTS, ASSIGNOR TO EVERLASTIK, INCORPORATED, OF BOSTON, MASSACHUSETTS, A CORPORATION OF MASSACHUSETTS.

NEEDLE-LOOM.

1,391,958.

Specification of Letters Patent. Patented Sept. 27, 1921.

Application filed January 5, 1921. Serial No. 435,155.

To all whom it may concern:

Be it known that I, SOLOMON KENDRICK, a citizen of the United States, residing at Chelsea, in the county of Suffolk and State 5 of Massachusetts, have invented new and useful Improvements in Needle-Looms, of which the following is a specification.

This invention relates to needle looms for weaving elastic or nonelastic fabrics, in 10 which the weft is laid by a needle in the open shed, and a selvage thread is passed through the loop of weft thread by a shuttle.

In accordance with my present improvements, I employ an oscillatory shuttle arranged to move about an axis transverse to the warp threads, so that a plurality of shuttles may be operated by a single transverse shaft extending across the loom. The needles and their operating bar and the shuttles and their operating shaft, are all supported by the breast beam or other appropriate stationary member of the loom, and simple power transmitting mechanism may therefore be employed for transmitting 25 power from the crank shaft to the needle-operating bar and shuttle-operating shaft.

On the accompanying drawing—

Figure 1 represents in front elevation a narrow-ware needle loom embodying my invention;

Fig. 2 represents a plan view with the arch or superstructure removed;

Fig. 3 represents, on a larger scale, a front elevation of a portion of the breast beam 35 with the instrumentalities supported thereby;

Fig. 4 illustrates, in plan view, a unit for a single web, comprising a needle and a shuttle;

Fig. 5 represents a section on the line 5—5 of Fig. 4;

Figs. 6 and 7 illustrate a shuttle which may be employed;

Fig. 8 represents an enlarged section on the line 8—8, Fig. 2;

Fig. 9 illustrates the mechanism for actuating the needle-operating bar;

Fig. 10 illustrates the same elements shown in Fig. 4, but in different positions;

Fig. 11 and 12 illustrate a shuttle holder, a shuttle and the operating device for the shuttle;

Fig. 13 illustrates a portion of the shuttle-operating shaft;

Fig. 14 illustrates one of the combined 55 bearings and shuttle races or holders;

Figs. 15 and 16 illustrate the mechanism for actuating the shuttle-operating shaft;

Figs. 17 to 19 inclusive illustrate the operation of the shuttle and the associated 60 needle;

Figs. 20 to 22 inclusive illustrate another form of shuttle suitable for the purpose;

Fig. 23 illustrates a bobbin.

Proceeding now to a description of the 65 loom which is shown upon the drawings, to the details of construction of which it will be understood the invention is not limited, the loom is provided with the mechanisms common to narrow ware looms by which 70 the warps for the several webs are advanced as the webs are woven, and tension is applied to the elastic warp threads, if elastic webs are being formed. In the end frames 30, 30 is journaled the usual crank shaft 31 75 by which the batten 32 is oscillated. The heddle frames are indicated at 33, any usual harness mechanism being employed and operated to form the shed according to the desired character of the weave—whether 80 plain or fancy. The batten is provided with the usual reed frames 34 for beating in the weft or filling; and there are the usual lease rods 35 for the warp threads of the several webs.

While I have shown the loom as 85 equipped to weave only six webs, it will be understood that this is merely for purposes of exemplification, as it may be of such length as to weave any usual or desired number of webs.

A characteristic of the illustrated loom is that the needles and the shuttles are all stationarily supported as by the breast beam 36. To this end I employ a plurality of brackets 37 which are secured by screws or 90 bolts 38 to the inner face of the breast beam, and which perform the several functions of supporting the needles and their operating bar, of supporting the shuttle operating shaft, and of serving as holders or races for 95 the shuttles, as will be described. Secured on top of the brackets by screws 39, there is a stationary bar 40, which is parallel with the breast beam; and to this bar is pivoted a plurality of needles 41, one for each web, 100 by pivot screws 42. As shown in Fig. 5, the bar 40 and upstanding flanges 43 on the brackets form a guideway for an operating 105

bar 44 having pins 45 engaging slots 46 in the tail ends 47 of the needles, so that as the bar is reciprocated the needles are oscillated about their respective pivots. Any suitable, 5 properly timed mechanism may be employed for reciprocating the bar, and preferably it should receive its power from the crank shaft. As illustrated, there is a bevel gear 48 (driven by gears 49, 50, from the crank 10 shaft), which, through a complementary gear 51, drives a shaft 52 journaled in bearings 53, 54 on the left hand end frame 30. The shaft 52 has a path cam 55, into the groove or path of which projects a roll or truck 56 15 on an arm or lever 57 pivoted at its lower end on a pin 58 supported by a stationary bracket 59 (see Figs. 8 and 9). The end of the bar 44 is twisted and upturned and is pivoted by a pin and slot connection with 20 the upper extremity of the lever 57, the pin being indicated at 60. By the mechanism just described the bar 44 is longitudinally reciprocated with a differential movement, halting temporarily at each end of its movement by reason of the shape of the groove or 25 path in the cam 55.

Each needle 41 is bowed in the shape of a hook, in plan view, as shown in Fig. 10, and has in its extremity an eye 61 through 30 which the weft or filling α passes, and in the bowed portion has a second eye 62 through which the filling passes to the eye 61. Hence when the needle is moved from the position shown in Fig. 10, where it is 35 out of the shed, through an arc to the position shown in Fig. 4, the weft is carried in the form of a loop into the shed, and the end of the needle projects for a considerable distance beyond the warp threads and 40 lies in front of the woven portion of the web. It will, in this connection, be observed that the pivot 42 for the needle is beyond one side of the web, so that the eyed end 45 of the needle may be easily swung into and out of the shed.

As each loop of filling is laid in a shed, a selvage thread is passed through it by a shuttle, as will now be explained. I have already stated that the brackets 37 afford 50 bearings for the shuttle operating shaft and races for the shuttles. For this purpose, each bracket, as shown in Figs. 11, 12 and 14, is provided with a bearing 63, and a lateral extension 64 which terminates in a 55 circular holder or race 65, having an opening or throat 66. Within each holder is an oscillatory shuttle 67 which carries a bobbin from which the selvage is drawn as required. As shown in Figs. 6 and 7, the shuttle has 60 an arcuate side 68 which fits in the race and terminates in a beak 69, and two flat sides 70, 71, forming a body which is recessed to receive a bobbin 72. On one face of the shuttle is the flat leaf spring 73, and on the other face is the hinged cover plate 74, held

in closed position by the pressure of the spring bearing on the flat side of the lug 75 through which the pintle 76 passes. The shuttle thread passes through an eye 77, suitable tension devices being employed, but not 70 shown in detail, since the shuttle *per se* does not differ from certain types of sewing machine shuttles.

Each shuttle is actuated by a shaft indicated as a whole at 78 and consisting of a 75 plurality of connected sections—one for each shuttle. The ends of the shaft are journaled in brackets 37, 79, the last mentioned bracket being supplemental to those at 37 and being located at the left end of 80 the loom as shown in Figs. 2 and 8. Each shaft section, a portion of one being shown in Fig. 13, comprises an end 80 which is journaled in the bearing 63 of one of the brackets, (which, of course, has a cap 81) 85 and is socketed or recessed to receive the end 82, of the next shaft section. A cross pin 83 connects the adjacent sections together. A flange 84 engaging the end of the bearing holds the shaft section against 90 longitudinal movement in one direction. Between its ends, each shaft section is enlarged, and is concavo-convex in cross section, as shown at 85 in Fig. 13, so that it may pass between the associated shuttle and 95 its race (see Figs. 11 and 12) and is provided with two fingers 86, 87 for loosely engaging the flat sides 70, 71, of the shuttle at points near the outer ends of said sides. Hence when the shaft is rocked in one direction or the other, the shuttle is likewise rocked thereby—there being a slight oscillatory play of the shuttle between the fingers, to permit the loop of needle or weft thread, 100 to pass around the shuttle as will be described. The fingers also tend to hold the shuttle in proper position in the race—the outer side of the shuttle and its beak being curved in an arc of approximately 180°.

The shaft 78 may be oscillated by any 110 suitable mechanism. As shown, however, the shaft 52, at the end of the loom has a cam 88 formed with a path or groove 89 into which projects a roll or truck 90, on the end of one arm 91 of a bell crank pivoted 115 by a pin 92 to an upstanding bracket 93, (on Figs. 15 and 16). The other arm 94 of the bell crank is connected by a twisted link 95 with the arm 96 of a lever by a pivot 97 passed through a slot 98. The 120 arm 96 is formed on a hub 99 loose on a shaft 100 mounted in suitable bearings 101 on the breast beam. The hub 99 has another arm 102 which is slotted as at 103, to receive a block 104 into which projects a pin 105 on a 125 third lever 106 which is secured to the shuttle shaft. The hub of the lever 106 bears against the bracket 79 and holds the shuttle shaft against longitudinal movement to the right. By reason of the construction described, 130

when the path cam 88 is rotated, the shuttle shaft is rocked back and forth, and is caused to dwell for a certain period with the shuttle in the position shown in Fig. 11, to be projected through a loop in the needle thread. In this case the beak 69 is just beyond the opening 66 in the shuttle race, and then when the loop of needle thread is laid in the opening, the shuttle is moved rapidly to the position shown in Fig. 12, to permit the beak to enter the loop and the shuttle to be carried through the loop, the loop of thread passing between the shuttle, and the shaft including the fingers thereof. The shuttle race is in such relation to its associated needle, that when the needle moves to the position shown in Fig. 4, one bight of the loop of needle or weft thread is laid in the recess in the path of the beak of the shuttle as shown in Fig. 5.

In Figs. 21 to 23 inclusive, I have shown a slightly different form of shuttle in which a relatively large bobbin 107 (see Fig. 24) may be employed. In this case, the body of the shuttle and the beak are similar to the corresponding parts in the shuttle previously described. The spring 108 is so bent as to extend laterally from the shuttle body and cross the bobbin and then bear at its free end 30 on the lug 109 of the hinged cover plate 110. The thread emerges through an eye 111, suitable tension devices, not shown, being employed as required.

The spools of needle thread are located in any suitable place, and between them and the needles are any convenient form of tension and take-up devices. If desired the spools, 112, may be placed on upright spin-dles 113 whose bases are placed on the floor 40 in the rear of the crank shaft as shown in Figs. 1 and 2. The needle or weft threads are carried upwardly and over tension and guide devices 114 on the arch 115, and thence downwardly through take-up devices 116 on 45 a bar 117, and under the top bar 118 of the support for the reed frames on the batten, to the needles. Each take-up device consists of a spring tensioned pivoted two arm lever having eyes 119 and 120 at the ends of the 50 arms, and is illustrated more or less conventionally as it does not *per se* constitute a part of the invention as herein claimed.

I shall describe the operation of weaving only one web, since all the others are woven 55 in the same way.

Assuming that the heddle frames have been moved so that the warp threads form a shed, the needle operating bar 44 is moved to the right to carry the needle 41 from the 60 position shown in Fig. 10 to the position shown in Fig. 4, (the shuttle at this time being in the position in Fig. 11) so as to lay one bight of the needle or weft thread in the opening 66 of the shuttle race 65; in

position for the beak of the shuttle to enter it. The needle dwells momentarily, while the shuttle is partially rotated to the position shown in Fig. 12, so that the loop of weft thread may pass around the shuttle; and the needle then moves in the opposite direction to draw the loop of weft thread back into the shed until the shuttle thread lies against the outside threads of the warp, whereupon the batten moves forwardly and the reeds beat the loop of weft thread into 75 the end of the shed. This operation is repeated with each shift of the warp threads to form a new shed.

To assist the rearward movement of the shuttle, I may provide a spring 122, one end 80 of which is secured to the shuttle-operating shaft 78, and the other end to the bearing bracket 79, as best shown in Figs. 2 and 10.

It will be observed that the shuttle races and the pivots for the needles are all stationarily supported by the breast beam or an equivalent part of the main frame, and are wholly independent of the batten, so that the movements or operations of the shuttles and the needles may be accurately coördinated and the parts positioned for effective coöperation. The shuttle-operating shaft is located below the plane of the webs so that the finished webs may pass over it as shown in Fig. 5, and hence I may, as previously described, employ a continuous shaft. The pivot for each needle is located in front of or beyond the fell of the web, as is, of course, each shuttle, and, by employing a curved needle, one bight of the loop of weft thread 90 may be laid accurately in the end of the shed, as best shown in Fig. 4, the two bights of the loop being separated by the passage of one of them through the thread eye or guide 62 located in the bowed or curved 95 portion of the needle, so that the beak of the shuttle may properly enter the loop.

Having thus explained the nature of my said invention and described a way of making and using the same, without attempting 110 to set forth all of the forms in which it may be made or all of the modes of its use, what I claim is:

1. In a needle loom, a curved needle, a stationary upright pivot therefor and means 115 for oscillating said needle to lay a loop of weft thread in the shed, in combination with an oscillatory shuttle arranged to enter and pass a selvage thread through said loop, a stationary shuttle race for supporting said 120 shuttle to move about an axis parallel with the breast beam, and mechanism for oscillating said shuttle.

2. In a needle loom, a curved needle having a thread eye in its free end and a thread 125 eye in its curved portion, a stationary pivot for said needle, and means for oscillating said needle about its pivot to lay a loop of

weft thread in the shed, in combination with an oscillatory shuttle arranged to enter and pass a selvage thread through said loop, and a shuttle-operating shaft having fingers for engaging said shuttle and journaled below the plane of the warp.

3. In a needle loom, an oscillatory needle and means for operating it to lay a loop of weft thread in the shed, in combination with 10 an oscillatory shuttle arranged to enter and pass a selvage thread through said loop, and movable about a horizontal axis transverse to and below the warp.

4. In a needle loom, shedding mechanism, 15 a stationary pivot located at one side of the web and in front of the fell, a bow-shaped needle movable about said axis and having thread guides in its free end and intermediate its ends for the weft thread, mechanism for oscillating said needle through 20 said web to carry the end of the loop of weft thread through said shed, a stationary shuttle race having a recess to receive the loop of weft thread, and an oscillatory shuttle in 25 said race arranged to enter said loop and lay a selvage thread therein.

5. In a needle loom, an oscillatory needle, a stationarily-supported pivot therefor located in front of the fell of the web, and 30 means for operating said needle to lay a loop of weft thread in the shed, in combination with an oscillatory shuttle arranged to enter and pass a selvage thread through said loop, and a stationarily-supported shuttle race in which said shuttle may oscillate 35 on a horizontal axis and having an opening to receive a bight of said loop, and a shaft located below the plane of the web and extending into said shuttle race and having 40 fingers for engaging and moving said shuttle.

6. In a needle loom the combination with 45 shed forming mechanism, a breast beam, an oscillatory needle supported by the breast beam, and mechanism for oscillating said needle to lay a loop of weft thread in the shed, of a shaft supported by the breast beam and arranged in parallelism therewith, and a shuttle operated by said shaft 50 for laying a selvage thread in said loop.

7. In a needle loom, the combination with 55 shed forming mechanism, an oscillatory needle movable about a vertical pivot beyond one side of the warp to lay a loop of weft thread in the shed, an oscillatory shuttle movable about a horizontal axis transverse to the warp threads to pass a selvage through the loop of weft thread, and mechanism for operating said needle and said 60 shuttle.

8. In a needle loom, the combination with 65 shed forming mechanism, an oscillatory needle movable about a vertical pivot beyond one side of the warp to lay a loop of

weft thread in the shed, an oscillatory shuttle movable about a horizontal axis transverse to the warp threads to pass a selvage through the loop of weft thread, a reciprocatory bar supported by the breast beam and movable longitudinally thereof for oscillating said needle, and a shaft longitudinal of the breast beam and supported thereby for operating said shuttle.

9. In a needle loom, a stationary circular shuttle race having an opening in one side 75 thereof, a shuttle therein movable about the axis of said race and having a beak and a bobbin, a shaft having means for imparting said movement to said shuttle, a pivoted oscillatory needle movable into the shed to 80 lay a loop of weft thread therein and into the opening of said shuttle race, and a stationarily-supported pivot for said needle located in front of the fell of the web.

10. In a needle loom the combination with 85 shedding means for the warps of a plurality of webs, and a needle for each web supported by the breast beam and adapted to lay a loop of weft thread in the shed, of a plurality of shuttles movable about a common axis, transverse to and out of the plane of the warp threads, and a shaft rotatable about said axis, and in operative engagement with all of said shuttles for moving 90 them about said axis.

11. In a needle loom the combination with 95 shedding means for the warps of a plurality of webs, and a needle for each web supported by the breast beam and adapted to lay a loop of weft thread in the shed, of a plurality of shuttles movable about a common axis, transverse to the warp threads, a plurality of shuttle races supported by the breast beam, and a shaft rotatable about 100 said axis, passing through said shuttle races, and having means for operatively engaging 105 all of said shuttles.

12. In a needle loom the combination with 110 shedding means for the warps of a plurality of webs, and a needle for each web adapted to lay a loop of weft thread therein, of a plurality of shuttles movable about a common axis, transverse to the warp threads, a plurality of shuttle races, a shaft passing through said races and comprising one section for each race provided with lateral fingers, and a shuttle in each race embraced by the fingers of the shaft section therein.

13. In a needle loom, mechanism for passing 115 selvage threads through loops of needle thread, comprising a plurality of brackets each having a bearing and an extension constituting a shuttle race, a shuttle-operating shaft journaled in said bearings below the plane of the woven webs and projecting 120 through said races, and a shuttle located in each said race and operatively engaging 125 said shaft.

14. In a needle loom, an oscillatory approximately arcuate needle which oscillates about a stationary vertical pivot to lay a loop of weft thread through the shed, a shuttle movable about a fixed horizontal axis and adapted to pass through the loop of weft thread and lay a selvage thread therein, a common driving shaft, and cam actuated mechanism actuated by said shaft for operating said needle and shuttle in ¹⁰ timed relation.
- 5

In testimony whereof I have affixed my signature.

SOLOMON KENDRICK.
